Atty.

UNITED STATES PATENT OFFICE.

JOHN P. FOLEY, OF GALESBURG, ILLINOIS.

CASKET-HANDLE.

1,202,987.

Specification of Letters Patent.

Patented Oct. 31, 1916.

Application filed May 11, 1916. Serial No. 96,868.

To all whom it may concern:

Be it known that I, JOHN P. FOLEY, a citizen of the United States, and a resident of Galesburg, in the county of Knox and State 5 of Illinois, have invented a new and useful Casket-Handle, of which the following is a specification.

The invention relates to handles, and particularly to that type or class thereof used 10 on burial-caskets.

One of the main objects of the invention is to provide a novel connecting-arm for the escutcheon-plate and handle-bar, the improvements being directed more particularly 15 toward the structural peculiarities thereof.

Another object is to provide novel features in that portion of the escutcheon plate which is engaged by said arm.

20 The principal object, therefore, is to generally improve the construction and increase the utility and efficiency of both members of devices of this character.

It is greatly to be preferred, not only in 25 order to provide great strength combined with lightness and attractive appearance, but for numerous other reasons, that handles of this nature be made of sheet metal, and in the accompanying drawings I have shown a 30 structure of that material.

In said drawings: Figure 1 is a front elevation showing the escutcheon-plate, one of the connecting or hanger-arms in position and the other omitted, and a fragment of the 35 handle-bar; Fig. 2, a perspective of the hanger-arm; Fig. 3, a vertical section, taken in the line 3-3 in Fig. 1; and Fig. 4, an end detail of the hanger-arm, a fragment of the handle-bar being shown also.

40 Considering the drawings in detail and indicating each element and, where necessary, each part thereof, by a distinguishing reference numeral, uniformly employed, 2 designates an escutcheon-plate preferably 45 formed from sheet-metal and the particular general shape or outline of which is immaterial. It is provided with openings 3, lips 4 and 5, and oppositely directed tongues 6, all adjacent said openings.

50 The hanger-arms 7 are die-cut and die-formed from sheet-metal and, like the plate 2, are preferably of sheet-steel, in order that the greatest strength and rigidity may be attained. After being formed, the general 55 cross-sectional outline of each arm is arcuate. Being identical, or duplicates, a description

of one will suffice. Each has at its inner end parallel ears 8 provided with registering apertures 8' in which the tongues 6 are inserted. An arcuate slit is cut by the forming die, substantially at the midlength of the arm and the relatively outer portions are then bent down to provide a clip portion 9 and a projection 10, the latter resulting from not turning down that portion of the 60 metal which lay within the boundaries of the slit. 11 indicates the resultant aperture. The continuation of the portion 9 is bent to form clip-portions 12 and 13, and the terminal 16 is brought down to lie between the 65 cheeks 14 and is held positioned by tongues 15. The portions 9, 12 and 13 constitute a handle-bar-engaging clip 21, and if the handle bar 17 be incurved or indented along its sides these portions are preferably bent as 70 shown in Fig. 3 to correspond therewith, whereby to cause the clip to firmly clasp 75 said bar.

When the arm 7 is raised to its weight-sustaining position the lip 4 constitutes a 80 weight-sustaining projection against which the flattened top 18 of the inner end of the arm 2 bears, whereby a greater weight may be sustained without distorting or tearing the metal adjacent it, than could if said lip 85 were omitted and the arm-top 18 bore against a raw edge, such as indicated at 19. Moreover, the portion 18 will bear against said lip 4 without marring or defacing the 90 plating or other finish on said arm. The lip 5 both reinforces the metal immediately below it and causes a smooth edge to be presented. It will be noted that when the handle 17 and arm 7 are raised to casket-carrying positions the arm-top 18 bears directly 95 upward—or in the direction of greatest resistance—on the plate 2, thus avoiding the backward thrust or thrust at right angles to the general plane of the plate, which backward thrust is likely to result in distortion 100 of the latter and even in tearing off the hanger-arms.

In drawing a casket from a hearse, and at some other times, the "pull" is longitudinally with reference to the hanger-arms. 105 In this operation reliance need not be placed altogether upon the tongues 6, for the hooks 25 will be drawn against the solid body of the plate 2.

By cutting the slit which results in the 110 opening 11 in the clip portion 9 I facilitate bending the clip 21 accurately and expedi-

tiously. In handles of this character it is important that they be of an attractive appearance. I have therefore sought to avoid the square or otherwise angular and therefore unattractive terminal-clip of preceding hangers, and instead thereof provide the projection 10 which not only adds refinement and attractiveness to the arm but obscures the said angular clip, the unfinished 10 appearance of which would be similar to the clip 21 were said projection 10 omitted. Another advantage is that this feature is attained economically and with facility, for there is no waste of metal, no additional operation, and no extra labor.

It will be evident without further description or illustration that an escutcheon plate having a single aperture, and a single hanger-arm may be used when desired, as 20 on very small caskets, in the usual manner.

Having thus described the nature of the invention I claim as new the following, to-wit:

1. The combination with a handle-bar, of 25 a hanger-arm including a clip bent therefrom and adapted to embrace said bar, one portion of said arm being slitted and the

resultant portion affording a projection extending beyond the clip.

2. The combination with a handle-bar, of 30 a hanger-arm including a clip bent therefrom and adapted to embrace said bar, one portion of the clip being slitted and the resultant unbent portion affording a projection which extends substantially in the general plane of the body of the arm.

3. The combination with a handle-bar, of 35 a hanger-arm including a body portion and a clip portion, the latter bent from the body portion and adapted to embrace said bar, 40 that portion of the clip which forms the outer end thereof being slitted and the material which is defined by said slit left unbent and lying in the same general plane with the body portion.

4. An escutcheon-plate having an aperture into which extend a pair of oppositely directed tongues, and having also a bearing-lip at the upper edge of said aperture and an integral reinforce-lip at the lower edge 50 thereof.

In testimony whereof I hereunto affix my signature this 8th day of May, 1916.

JOHN P. FOLEY.
